RADIO SHIELDED SPARK PLUG

Hector Rabezzana, Flint, Mich., assignor to General Motors Corporation, Detroit, Mich., a corporation of Delaware

Application July 15, 1940, Serial No. 345,476

3 Claims. (Cl. 123—169)

My invention relates to radio shielded spark plugs designed to prevent high tension current supplied to the insulated electrode of a spark plug from interfering with the operation of adjacent radio receiving apparatus; and the same comprises improved metallic shielding features associated with and enclosing the supply conductor leading to the insulated electrode of the plug, and which shield is conductively connected to the engine structure so that electrical waves, due to high tension oscillating current in the supply lead, are grounded by the shield and prevented from being radiated into the adjacent space. Specifically, my invention consists in improved terminal connector features for providing a conducting path through which current is supplied to the insulated electrode of the plug, in providing better insulation than heretofore between the high tension supply conductor and the grounded shell or casing of the plug, and in otherwise improving radio shielded spark plugs as hereinafter and at length appears. The drawing accompanying and forming a part of this specification illustrates the preferred form of my invention, and therein:

Figure 1 is a view showing a section of my improved radio shielded spark plug taken upon a central plane extending longitudinally thereof.

Figure 2 is a view showing a section upon a transverse plane indicated by the line 2—2, Figure 1, upon a much larger scale.

Referring now to the drawing, my improved shielded spark plug comprises a hollow tubular shell or casing 5 made commonly of low carbon or machinery steel, and the lower end of which is externally threaded at 6 to screw into a threaded hole in the wall of an internal combustion engine cylinder. The upper end of this shell is threaded to receive the threaded lower end of a metallic shield tube 7 which in effect is a part of the casing, and the upper end of this shield tube is threaded to receive a coupling member 8 whereby a current supplying lead 9 may be connected to the spark plug. The supply lead includes as a part thereof an external metallic sheath 10 which ordinarily extends throughout the length of the supply lead and forms a conducting shield or casing therefor which is grounded to the engine with which the plug is used through the coupling member 8, the shield tube 7 and the shell or casing of the plug. The sheath 10 may be in the form of tubing as shown, or in the form of a braided or woven covering for the lead in which case it is commonly associated with a terminal nipple with which the coupling

member engages to secure the lead to the tubular casing 7.

Within and extending throughout the length of the casing 5 is a tubular insulator 11 made from porcelain or equivalent ceramic or dielectric material suitable for withstanding the high temperature and strains met with in spark plugs; said insulator having an inclined shoulder 12, and being supported by an internal ledge 13 within the shell 5. This insulator is held in place within the casing 5 by a stiff but resilient holding gasket or washer 14 C-shaped in cross section, and commonly made of spring steel and acting between an annular washer 15 at the upper end of the insulating member 11, and an internal annular ledge 16 within the shield tube 7; and which C-shaped washer is compressed and distorted and subjected to stress which acts to force the insulating member downward and toward the ledge 13 as the shield tube 7 is screwed into the upper end of the casing 5. The numeral 17 designates a cooling sleeve of soft copper surrounding the lower end of the insulating member 11 and fitting within the lower end of the shell 5, 25 and the purpose of which is to provide a good heat conducting path from the insulating member to the shell of the plug and to the cylinder of the engine, so that the temperature of the insulated electrode 19 and of the insulator 11 will be kept as low as possible. The lower end of the cooling sleeve has a metallic gasket 18 U-shaped in cross section which is clamped between shoulder 12 and the ledge 13, and which acts to hold the sleeve 17 in place and to provide a 30 gas-tight packing between the insulating member and the shell of the plug. The insulated electrode 19 is in the form of a bevel-headed screw having a threaded portion 20 at its upper end as shown, which screws into a similar threaded portion at the upper end of the passage provided for the electrode in the insulating member 11; a suitable gasket 21 being commonly provided between the inclined head 22 of the electrode and the insulating member to seal the joint 35 between the electrode and the upper end of the passage through which it extends.

The numeral 23 designates a tubular member made of bakelite or equivalent insulating material and which forms a terminal or tip for the 40 current supply lead 9. The lower end 24 of this terminal member is of a diameter such that it may enter into the upper end of the insulating member 11, as shown; and the upper end 25 of this terminal member lies within the upper end of 45 the metallic shield 7 when the supply lead is

connected to the plug through this terminal member. Said upper end has a passage into which the supply lead 9 enters and within which it fits closely, the terminal or tip being in effect a part of the supply lead and coming away there-with when said lead is disconnected from the plug. The upper end of the member 23 extends to the upper end of shield tube 1 of the plug and the same is held in place within the plug structure, and the supply lead 9 is secured to the plug, by the coupling member 8; this being accomplished in the embodiment of my invention illustrated by providing the metallic casing 10 with an internal ledge 26 which overlies the upper extremity of the member 23 so that the act of screwing the coupling member onto the shield tube forces the terminal member downward and secures the supply lead to the plug structure; the terminal member, as hereinbefore pointed out, being in effect a unitary part of the supply lead.

The current supply lead 9 comprises a metallic conductor 27 of small diameter surrounded by comparatively thick insulation 28 of rubber or like material; and the conductor has a terminal comprising a head 30 of ball or like form and an extension 31 shaped like a cork-screw and which, as it is screwed into the insulation 28, establishes a connection with the conductor 27 through which high tension current is supplied to the insulated electrode 19 of the plug through a metallic rod 32 extending through a passage in the tubular member 23 and having a resilient socket 33 at its upper end which clasps the head 30; and a spring 34, the upper end of which is held between washers 35 and the lower end of which contacts 36 with upper surface of the head end 22 of the insulated electrode 19. The parts 32, 33 and 34 are permanently assembled with the terminal member 23; and although the detachable connection provided by the socket 33 and head 30 permits the supply lead 9 to be pulled out of the passage in the member 23 into which it extends without difficulty and another lead to be substituted therefor, it is contemplated that the terminal member 23 shall remain assembled with the current supply lead 9 so as to form permanently attached terminal or tip therefor as hereinbefore explained.

In assembling the insulating member 11 with the shell 5 and shield tube 1 the tube is screwed into the upper end of the shell, thus compressing and stressing the C-shaped gasket 14, after which the shell is subjected to longitudinal compression while a thin wall section 36 thereof is heated by a current of electricity made to flow therethrough, thus providing a more perfect gas-tight joint between the upper end of the insulating member and the shield tube; and it will be appreciated that two concentric insulating members both extending beyond the upper end of the shell or casing 5 are present in my improved shielded plug, one being the upper end of the insulating member 11 and the other being the lower end of the terminal member 23.

Having thus described and explained my invention, I claim and desire to secure by Letters Patent:

1. In a shielded spark plug, a hollow tubular shell or casing having a threaded portion at its lower end, and a metallic shield tube extending upwardly therefrom; a tubular insulating mem-

ber supported within said shell or casing and extending into the lower end of said shield tube; means for securing said insulating member in place within said shell; an insulated electrode carried by and extending from the lower end of said insulating member; a tubular terminal member made of insulating material within said shield tube and extending downward and into said insulating member; an insulated current supply lead extending into the upper end of said terminal member, and which lead has an external metallic sheath; means for securing said metallic sheath to the upper end of said shield tube; and means permanently assembled with said tubular terminal member for providing a current conducting connection between said supply lead and said insulated electrode.

2. In a shielded spark plug, a hollow tubular shell or casing having a threaded portion at its lower end, and a metallic shield tube extending upwardly therefrom; a tubular insulating member supported within said shell or casing and extending into the lower end of said shield tube; means for securing said insulating member in place within said shell; an insulated electrode carried by and extending from the lower end of said insulating member; a tubular terminal member made of insulating material within said shield tube and extending downward and into said insulating member; an insulated current supply lead extending into the upper end of said terminal member, and which lead has an external metallic sheath; means for securing said metallic sheath to the upper end of said shield tube; and means permanently assembled with said tubular terminal member for providing a current conducting connection between said supply lead and said insulated electrode.

3. In a shielded spark plug, a hollow tubular shell or casing having a threaded portion at its lower end, and a metallic shield tube extending upwardly therefrom; a tubular insulating member supported within said shell or casing and extending into the lower end of said shield tube; means for securing said insulating member in place within said shell; an insulated electrode carried by and extending from the lower end of said insulating member; a tubular terminal member made of insulating material within said shield tube and extending downward and into said insulating member; an insulated current supply lead extending into the upper end of said terminal member, and which lead has an external metallic sheath; means for securing said metallic sheath to the upper end of said shield tube; a metallic rod extending through a passage in the lower end of said tubular terminal member and permanently secured therein; a head at the lower end of said current supply lead; a resilient socket secured to the upper end of said rod and adapted to clasp said head, to thereby provide a detachable connection between said rod and said head; and means for providing a current conducting connection between the lower end of said rod and said insulated electrode.

HECTOR RABEZZANA.
